UNITED STATES PATENT OFFICE.

JULIUS R. HALL, OF OAK PARK, ILLINOIS, ASSIGNOR, BY MESNE ASSIGNMENTS, TO THE BOOTH ELECTRIC FURNACE CO., OF CHICAGO, ILLINOIS, A CORPORATION OF ILLINOIS.

FURNACE-DOOR.

1,366,072.

Specification of Letters Patent. Patented Jan. 18, 1921.

Application filed April 4, 1918. Serial No. 226,575.

To all whom it may concern:

Be it known that I, JULIUS R. HALL, a citizen of the United States, residing at Oak Park, in the county of Cook and State of Illinois, have invented a new and useful Improvement in Furnace-Doors, of which the following is a specification.

This invention relates particularly to furnace doors and is especially valuable in electric furnace construction.

The primary object is to provide a door of simple and durable construction, which can be opened and closed with great facility, which will effect a very close joint, and which will be largely free from danger of warpage.

The invention is illustrated in its preferred embodiment in the accompanying drawings, in which Figure 1 represents a broken plan view of a furnace equipped with a door in accordance with the invention; Fig. 2, a broken elevational view of the same; Fig. 3, a broken vertical sectional view taken as indicated at line 3 of Fig. 1; Fig. 4, a broken, front elevational view; Fig. 5, a perspective view of one of a pair of pivot lugs with which the intermediate portion of a counter-balanced yoke which supports the door is equipped; Fig. 6, a broken perspective sectional view of the upper portion of the frame of the door-opening; and Fig. 7, a perspective sectional view of a detachable insert member with which the frame of the door-opening is equipped at its upper portion.

In the construction illustrated, A represents the body of a furnace, whose vertical wall is provided with a door-opening A¹; A², a door-opening-frame secured to the vertical wall of the furnace-body; B, a vertically-swinging counter-balanced door-carrying yoke or member whose arms are connected by pivotal supports B¹ with the body of the furnace; B², a vertically-shiftable door on pivotal mountings B³ connected to the intermediate portion of the yoke B; and C, mechanism for actuating the door. The door-carrying member B is adapted to swing about horizontal pivots in the rear of and preferably somewhat above the door-opening; and the pivotal connections of the vertically shiftable door describe arcs in front of the plane of the face of the frame of the door-opening in such

manner that the door will be forced against the face of said frame as the door approaches the completely closed position while sliding in contact with the frame of the door-opening.

The door is shown applied to the vertical wall of an electric furnace of circular horizontal cross-section. This wall comprises the usual steel shell 1 and fire-brick lining 2, through which the door-opening A¹ is made. The frame A² preferably comprises an annular casting which has an external flange 3 which is riveted to the shell 1. At the upper portion of the annulus, the flange 3 is discontinued, and the ring is formed to afford a seat for a detachable plate 4. The upper portion of the annulus comprises a web 5 which lies in the same plane as the flange 3 and is provided with forward-extending flanges 5^a. The frame has a raised flange 3^a which is segmental in form, and which has at its ends, at the upper portion of the frame, the offset portions or shoulders 3^b which form a junction with the extremities of the inner flange 5^a. The plate or insert 4 has a horizontal flange 4^a which is adapted to form a lining for the inner surface of the upper portion of the annulus A², while the plate 4 forms a facing which covers the flanges 5^a. The plate 4 is further provided with diagonal corner shoulders 4^b which rest upon the shoulders 3^b. Thus, the detachable plate 4 has a sort of inter-locking relation with the upper portion of the annular frame-member A²; and the parts are secured together by means of suitable bolts 6. The plate 4 serves to protect the upper portion of the annulus from the destructive influence of the fire when the door is open; and the plate 4 may be replaced by a new plate, when necessary.

The yoke B comprises an intermediate portion 7 which is disposed in front of the door B², and divergent arms 7^a which are equipped near their extremities with pivot lugs 8 which form portions of the pivotal supports B¹. The lugs 8 are connected by pintles 9, with pivot-brackets 10, which are riveted to the shell of the body A. The extremities of the arms 7^a of the yoke are equipped with counter-weights 11. Thus, the yoke B loosely embraces the front wall of the furnace and is adapted to swing about a horizontal axis which is located

back of the door-opening whereby the yoke will carry the door B^2 to the open position shown by dotted lines in Fig. 2.

The yoke B may conveniently comprise an angle-iron bent to the required form. To the flanges of this angle-iron, near the junction of the intermediate portion 7 with the oblique arms 7^a, are secured pivot-lugs 12, which form portions of the pivotal mountings B³ of the door. These pivot lugs 12 are provided with perforations 12^a which receive the pintles 12^b which project from lateral bosses 12^c with which the door is equipped a little above the center thereof.

15 The door B^2 , in the construction illustrated, comprises a frame 13 in which are suitably secured fire-bricks 14. The inner surface of the door presents a flat face which rests against the annulus A^2 forming 20 the frame of the door-opening. The door opens and closes by a vertical shifting movement, when the yoke B is swung on the horizontal pivots B¹. The pivotal connections B³ between the yoke and the door are 25 above the center of gravity of the door, so that the door will always hang in a vertical plane. The door is of sufficient weight to considerably more than overcome the counter-weights 11, so that the door will tend 30 to slide downwardly along the outer face of the frame A^2 of the door-opening and wedge itself firmly between the yoke B and the frame of the door-opening. This results not only in a close joint, but tends 35 to prevent warping of the frame of the door opening. The door itself may be made of very staunch construction and of heavy weight, so that it will have no tendency to warp, and will aid in maintaining the frame 40 A^2 against warping.

The mechanism C for opening the door may comprise simply a link 15 connecting one of the arms 7^a back of its pivotal support with a foot-lever 16. This foot-lever 45 may be disposed to lower the counter-weighted end of the yoke and lift the door B^2 to the elevated or open position. The door may be supported in the open position by means of a link 17 which has its upper 50 end pivotally connected with a lug 18 carried by one of the arms 7^a. The link 17 works through a loop or guide 19 secured to the body of the furnace, and is provided with a series of perforations 17^a, any one 55 of which may be caused to register with a perforation 19^a with which the loop 19 is provided. The link 17 may be held in adjusted position by means of a pin 20.

From the description given it will be understood that the door B^2 may be shifted from the closed position shown in full lines in Fig. 2 to the dotted line position shown in Fig. 2 by simply depressing the foot-lever 16. A pin may then be passed through 60 the perforation 19^a of the loop and a regis-

tering perforation 17^a of the link 17 to hold the door in open position. When the pin is removed, the door will automatically close, or fall of its own weight to the position shown in full lines in Fig. 2; and in this 70 operation the door will wedge itself firmly between the bearings of pivots B³ and the frame A^2 of the door-opening, with which the door has sliding contact. If desired, the device C may be omitted, and the door 75 may be opened by simply lifting upon the intermediate portion 7 of the yoke B.

It will be understood that the construction described is simple, durable, affords a close joint, and is largely free from danger of 80 warpage. The door will close automatically when permitted to do so, and will firmly wedge itself in the closed position. While the improved door was primarily designed for use in connection with electric furnaces, 85 it may be advantageously used for fire-chambers or heating chambers wherever desired.

The patent of William K. Booth, No. 1,244,415, granted October 23, 1917, describes the use of an auxiliary electrode for 90 use in the preliminary heating of an electric furnace. Such auxiliary electrode may extend either through an integral part of the furnace-wall, or through an auxiliary door. The present invention may be used either 95 alone, or the improved door may be used in co-operation with another or auxiliary door in which is mounted an auxiliary electrode, as described in my co-pending application, No. 226,576 filed of even date 100 herewith.

The foregoing detailed description has been given for clearness of understanding only, and no unnecessary limitation should be understood therefrom, but the appended 105 claims should be construed as broadly as permissible in view of the prior art.

What I regard as new and desire to secure by Letters Patent is—

1. The combination with a vertical furnace-wall provided with a framed charging door-opening, of a door-carrying member mounted to swing about horizontal pivots, and a door connected with said member by horizontal pivots which approach the plane 115 of the face of the frame of the door-opening in the closing operation, said door having a rear contact surface adapted to make sliding contact with the face of the frame of the door-opening, said construction being 120 such that the door will be forced against the face of the frame of the door-opening in the closing operation.

2. The combination with a vertical furnace-wall provided with a door-opening, of 125 a yoke supported on horizontal pivots which are parallel with the plane of the door-opening and so disposed as to cause the intermediate portion of the yoke to describe an arc which approaches the plane of the door- 130

opening as the door nears the completely closed position, and a self-adjusting door suspended at its intermediate portion on the intermediate portion of said yoke, said construction being such that the door will be forced against said wall by the action of said yoke when the door is closed.

3. The combination with a vertical furnace-wall provided with door-openings, of a yoke having an intermediate portion adapted to pass in front of the door-opening and having rearwardly-extending arms, pivotal connections between said arms and the wall of the furnace so disposed as to cause the intermediate portion of said yoke to approach the furnace as the door nears the completely closed position, and a door suspended at its intermediate portion on said yoke and disposed between the intermediate portion thereof and the wall of the furnace, whereby the door will be forced against the face of the door-opening as it moves to the completely closed position.

4. The combination with a furnace-wall

provided with a door-opening disposed in a vertical plane, a door-carrying member having arms connected by horizontal pivots with the wall of the furnace at points in the rear of the upper portion of the door-opening, and a self-adjusting door suspended on said member and so disposed with relation thereto as to be forced into close contact with the wall as the door reaches the completely closed position.

5. The combination with a furnace-wall provided with a door opening, of a mounting carried by horizontal pivots so disposed relatively to said door opening as to cause portions of said mounting to describe an arc which approaches the plane of the door opening as the mounting carries the door to its completely closed position, and a door having horizontal pivotal connections with said arc-describing portions of said mounting at an axis slightly above the center of gravity of said door.

JULIUS R. HALL.
